UNITED STATES PATENT OFFICE.

GEORGE C. RICHARDS, OF BERKELEY, CALIFORNIA, ASSIGNOR TO RICHARDS GAS AND FUME CONDENSER CO., OF OAKLAND, CALIFORNIA, A CORPORATION OF CALIFORNIA.

FUME-CONDENSER.

No. 895,790.

Specification of Letters Patent. Patented Aug. 11, 1908.

Application filed August 15, 1907. Serial No. 388,720.

To all whom it may concern:

Be it known that I, GEORGE C. RICHARDS, citizen of United States, residing at Berkeley, in the county of Alameda and State of California, have invented new and useful Improvements in Fume-Condensers, of which the following is a specification.

My invention relates to an apparatus for condensing and absorbing smoke and fumes from smelters, and from garbage or other crematories, furnaces and smoke-stacks.

The object of the present invention is to provide a simple, practical means for condensing or absorbing noxious vapors and fumes.

The invention consists of the parts and the construction and combination of parts as hereinafter more fully described and claimed, having reference to the accompanying drawings, in which—

Figure 1 is a vertical sectional view of the apparatus. Fig. 2 is a detail view of a baffle. A represents a smoke-stack, through which arise all the smoke, fumes and vapors from the combustion chamber or furnaces. The top of the stack has a water-jacketed bend 2, which leads into a horizontal conduit portion 3. The receiving end of this conduit is contracted or choked, as shown at 4, and the jet of steam or spray of water is discharged through this throat portion, through a nozzle, as 5, in the direction of the line of travel of the smoke and vapors. The object of the jet is to induce a strong draft through the stack and condensing apparatus.

The conduit is suitably lined to protect the outside metal from the acids. Under most conditions this lining may be of wood.

The discharge end of the conduit 3 opens into an enlarged receiving chamber 6, which is preferably round or rounded, and lined with wood or cement. The bottom of the chamber 6 has an opening into a condensing and collecting conduit 7. This conduit 7 is preferably made with a vertical portion with connections with the chamber 6, and with an inclined continuation 7'. The interior of the vertical portion is preferably provided with the interior baffles 8 which may be annular, and which have their upper surfaces sloping downward and inward, so that any water passing down the conduit 7, on striking these baffles will be shot from all sides toward the center of the conduit. The extension 7' of this condensing conduit or tube is provided

with short, spirally - arranged, angle - iron riffles or baffles 9, alternately arranged on the bottom and part way up the sides of the section 7', in such fashion that any water flowing down this inclined tube will be washed from side to side, falling from one baffle to another in the form of a series of cascades, with the effect that the tube will be practically filled with spray.

Suitably arranged in the chamber 6, so as to discharge in line with the tube or conduit 7, is a hydraulic nozzle 10 having a suitable regulating valve 11; and this nozzle is adapted to discharge a column of spray downward and into the tube. Preferably the upper end 70 of the tube is expanded, as shown at 7^a.

In practice, the smoke and vapors rising through the smoke - stack are forced by means of the nozzle 5 into the receiving chamber 6. If a water jet is used at the nozzle 5, a primary condensation and absorption of the smoke and vapors take place in the extension 3. In the chamber 6 the direction of travel of the vapors is changed, so that the final outlet may be close to the ground, or 80 near the level on which the furnace is situated. The rounded chamber 6 is preferred, as it obviates back pressure in the smoke-stack.

The water discharge from the nozzle 10 acts to force the vapors downward through the discharge and condensing conduit 7—7', with gravity aiding the pressure of the water.

The series of baffles 8—9 in the conduit operate as above described to create a series 90 of cascades, substantially filling the entire conduit with a column of spray, and so bringing every particle of smoke and fumes into intimate contact with the water particles to insure absolute condensation or absorption. At the same time, this falling column of water and spray in the conduit 7—7' accelerates the draft through the furnace.

There is no limit to the size or application 100 of this apparatus.

While it has been especially designed for use in connection with smelters, it is equally applicable for use in smoke-stacks of factories, battle-ships, or wherever it is desired 105 to remove or conceal all external evidences of combustion. In fact, on war-ships it would be of great value, because its use would prevent detection of the vessel by the enemy through the medium of the escaping 110

smoke. Often a vessel is located long before she is seen, by the column of smoke rising from her smoke-stacks.

Having thus described my invention, what I claim and desire to secure by Letters Patent is—

1. In an apparatus for condensing vapors, the combination of a stack having a lateral extension and a receiving chamber at the 10 end of said extension, a tubular conduit leading downwardly from said chamber, a hydraulic nozzle discharging into said conduit, and baffles on the inside of the conduit arranged to throw the water and spray toward 15 the center of said conduit.
2. In an apparatus for condensing vapors, the combination of a stack having a lateral extension, a receiving chamber at the end of 20 said extension, a tubular conduit leading from said chamber, a hydraulic nozzle arranged to discharge into said conduit, baffles in the conduit acting on the water from said nozzles to project the water in a series of 25 cascades toward the central axis of the conduit, said conduit having an inclined tubular extension with oppositely arranged spiral riffles.
3. In an apparatus for condensing vapors, the combination of a stack having a lateral 30 extension, said extension having a contracted throat portion at its receiving end, a nozzle

discharging through said throat portion in the direction of travel of the vapors to create a forced draft through the extension, a rounded receiving chamber at the discharge 35 end of said extension, said receiving chamber having a downward extending outlet, a conduit connected with said outlet, and a nozzle in the receiving chamber discharging through said outlet.

4. In an apparatus for condensing vapors, the combination of a stack having a lateral extension, said extension having a contracted throat portion at its receiving end, a nozzle discharging through said throat portion in the direction of travel of the vapors to create a forced draft through the extension, a rounded receiving chamber at the discharge 40 end of said extension, said receiving chamber having a downward extending outlet, a conduit connected with said outlet, and a nozzle in the receiving chamber discharging through said outlet, said conduit having internal baffles operative to create a series of cascades therein.

In testimony whereof I have hereunto set my hand in presence of two subscribing witnesses.

GEORGE C. RICHARDS.
